ENGINE

Edward Whritenour, Haledon, N. J.

Application July 26, 1938, Serial No. 221,293

9 Claims. (Cl. 123—11)

This invention relates to rotary internal-combustion engines, and more particularly it relates to engines of this class characterized by a rotor turning always in one direction and a piston which, while rotatively progressing around the axis of and in the rotor, does so intermittently, the rotor and piston for that purpose being inter-geared.

The rotor in my engine is cylindrical and arranged coaxially of and in the cylinder and in and coaxially of the rotor is the piston. The rotor and piston have alternating partitions extending lengthwise of the cylinder axis and dividing the rotor interior into four independent working spaces. The cylinder has two pairs of openings, each pair comprising an intake and an exhaust, and the four working spaces of the rotor respectively have ports, and there is a peculiar coordination of these openings and ports whereby, without valves as independently movable parts, each working space is active during every revolution of the engine, that is, undergoing one of the intake, compression, explosion and exhaust stages; further, so far as the engine proper is concerned, there need be only six moving parts, for instance, in the example to be set forth, rotor, piston, two planet-gears in mesh with a fixed gear forming, in effect, a part of the cylinder, and two links to connect said planet-gears, respectively, with eccentric points, as of a double crank, of the piston structure.

Other unique features are hereinafter set forth, among which is the circumstance that the ignition and lubricating are accomplished in a quite simple and reliable manner and obtain actuation directly from the rotary parts of the engine.

In the drawings,

Fig. 1 is a vertical sectional view of the engine in the vertical plane of the axis of piston shaft 17 but showing the piston and the near rotor head 13 in elevation;

Figs. 2 and 3 are sections on lines 2—2 and 3—3, respectively, Fig. 1;

Fig. 4 is a section on line 4—4, Fig. 1, with the fins 7 appearing in elevation and some of them omitted;

Fig. 5 is a side elevation of the rotor;

Fig. 6 is a section on lines 6—6, Fig. 5;

Fig. 7 is a right-hand end view of the rotor and piston, with the latter partly in section on line 7—7, Fig. 5;

Fig. 8 is a fragmentary plan of piston shaft 17;

Fig. 9 is a side elevation of a modified form of crank included in the transmission;

Fig. 10 shows the piston with its shaft in section and its blades in side elevation and the rotor in section;

Fig. 11 is a top plan of the cylinder with the fins omitted; and

Figs. 12, 13 and 14 are a side, plan and isometric fragmentary view of an improved form of sealing device.

The cylinder, generally designated A in Figs. 1, 4 and 11, is formed by the cylindrical shell 1 and heads 2 and 3, each head forming a housing and being secured to the shell by screws 4. Axially offset from each other the shell has two pairs of openings 5—6 and 5a—6a; openings 5—5a may be taken as intakes and openings 6—6a as exhausts, or vice versa, the former being the intakes if the direction of rotation of the engine (viewed from the right) is clockwise. The intakes have equal leads on the exhausts, or are equally advanced relatively relative to the exhausts. For a purpose to appear the openings 5—6 have a lead on or are offset rotatively with respect to the openings 5a—6a. The cylinder may have provision for cooling it, as fins 7. The head 2 provides an internal annular seat at 2a and head 3 a similar seat at 3a, both concentric therewith.

In the cylinder is mounted a rotor acting as a valve, being generally designated B in Figs. 5 to 7 and formed as follows: A cylindrical shell 8, having sealing rings 8a, has heads 9 and 10 fast thereto and the heads have axial and outward tubular projections or shafts 9a and 10a respectively equipped with hardened metal conical bearing collars 9b and 10b between which and the respective seats 2a—3a are the bearings 11 and 12 for the rotor. The shell part of the rotor has internal diametrically opposed counterpart heads or partitions 13 extending from end to end thereof and whose opposite longitudinal faces are radial to the rotor axis, said heads having their adjoining faces shaped to fit a certain shaft 17 to be referred to and with which the heads coact to divide the shell-interior into two equal spaces. In the zones of the respective pairs of ports 5—5a and 6—6a the shell has pairs 14 and 14a of slot-like ports, the ports of each pair being diametrically opposite each other. The ports are formed in part through the partitions, two ports 14—14a leading to one and the other two 14—14a to the other of the mentioned spaces. Further, in the central zone of the rotor and respectively aligned with and inward of these ports the rotor is formed with holes 15 which extend through the partitions or heads 13 in bias relation to a

plane bisecting such heads, those at either side of the rotor crossing each other and leading to the respective spaces. These are to receive the spark-plugs 16.

5 In and rotative in the same direction as the rotor, but intermittently, is a piston generally designated C in Fig. 4. This comprises a shaft and blades acting as piston-heads and projecting oppositely from the shaft or in the same diametric 10 plane. The shaft, 17, has opposed longitudinal grooves 18 and, joining the grooves, a slot 18a, the grooves extending beyond the ends of the slot to form recesses 18b (Fig. 8) for a purpose now to appear. Seated in the grooves are the 15 blades forming piston-heads or partitions 19, each having terminal lugs 19a fitting said recesses. The ends of the shaft are journaled in annular bearings 20-21 arranged in bearing housings formed in the rotor shafts as shown in 20 Fig. 1, and these receive said lugs and serve to confine the heads 19 against centrifugal displacement. The heads or partitions 19 of the rotor being contoured at 19b to fit the shaft and the piston-heads being equipped with sealing strips 22 at their outer and end margins (diagrammatically shown in Figs. 4, 6 and 10, but see hereafter), each of the mentioned spaces is divided to form four independent working spaces, or two designated 23 and two designated 25 23a. The space 23 are to communicate via their ports 14 with the corresponding openings 5-6 and the spaces 23a are to communicate via their ports 14a with the corresponding openings 5a-6a. As will appear, just as the one pair of openings 30 5-6 has a lead on (by which I mean is offset rotatively relatively to) the other, so the corresponding pair of ports 14-14 has a lead on the other pair, and in the same direction and to substantially the same extent.

35 40 For each cycle of rotation of the rotor and piston around the axis of shaft 17 the piston is twice to be retarded so that its rotation is intermittent. For this purpose the rotor and piston are suitably intergeared, as by the following transmission: Fast to head 3 is a sun-gear 24 and fast to shaft 10a of the rotor is a disk 25 in which is journaled a pair of planet-gears 26 meshing with the sun-gear, the sun-gear being twice the size of each planet-gear. On the corresponding end of the shaft is a crank 27 having diametrically opposed arms and on each planet-gear is a crank 28, such cranks being respectively connected with the arms of crank 27 by links 29.

45 For the purpose of description of the operation 50 we shall assume that the rotation is clockwise (viewed from the right), though it might be anti-clockwise; due to the intermittent rotation of the piston each working space is twice contracted and expanded in each cycle. With regard to either working space of the class 23 the intake will be from opening 5 via port 14 for such space and the exhaust will be via said port to opening 6; with regard to either working space of the class 23a the intake will be from opening 5a via port 14a for such space and the exhaust will be via said port to opening 6a. In Fig. 4 the right and left working spaces 23 are respectively undergoing intake and explosion, and the right and left spaces 23a undergoing 55 compression and exhaust (the piston now undergoing retardation); when the rotor has turned past that position at which the piston begins to retard these several spaces, 23-23a-23-23a, reading clockwise, will be undergoing, respectively, compression, explosion, exhaust and in-

take; and so on. The intake and exhaust openings 5-6 for the one pair of working spaces 23 have a lead on the other pair (to wit, in the same rotative direction and to substantially the same extent as the corresponding ports 14 have 5 a lead on the ports 14a) so that initiations of successive cycles of the intake, compression, explosion and exhaust stages affect the working spaces (reading anti-clockwise) successively, which would not be the case otherwise. 10

Succinctly considered the invention contemplates, then, a cylinder, a hollow cylindrical rotor coaxial with and in the cylinder, a piston in and coaxial with the rotor, said piston and rotor respectively having pairs of partitions extending 15 lengthwise of the cylinder axis and alternating with each other and together forming in the rotor four independent working spaces, means to fire the charges in said spaces, and means intergearing the rotor and piston for rotation in a common direction and with retardation of the piston at substantially two equal intervals in each cycle of rotation of the rotor, said cylinder having passaged means for intake and exhaust and said rotor constituting a rotary valve for such 20 25 passaged means and having ports arranged to connect the successive spaces with said passaged means successively in each cycle of rotation of the rotor.

In the example, said passaged means consists 30 of openings, as the pairs 5-6 and 5a-6a, offset from each other axially of the cylinder and having the openings of each pair forming intake and exhaust and the two intakes having leads in one rotative direction on the exhausts; and the 35 rotor has ports leading to its respective working spaces and the alternate and remaining ones of such ports entering the rotor at points in the zones of and adapted to communicate with the respective pairs of openings; and one pair of 40 openings and the pair of ports communicating therewith have leads on the other pair of openings and ports, respectively, in the same rotative direction and to substantially equal extents.

To provide a desirable yield to the transmission, cranks such as that shown in Fig. 9 and corresponding to cranks 28 may be used. This comprises a carrying member 30 whose axis is at 30a and which has a bearing stud 30b and an arcuate groove 30c concentric with such stud. 45 On the latter is oscillatory a carried member 31 having a stud 31a to which link 29 may be connected and a stud 31b in the groove. The latter contains springs 32 to cushion the thrust of stud 31a and hence the carried member, allowing 50 at times the yield in the transmission. 55

Ignition is provided for as follows: at 33 in housing 2 is a fixed ring-gear. Fixed to shaft 9a and within the housing is a housing 34 in whose wall 35 is journaled a member having a gear 36 meshing with the ring-gear and also having a pinion 37. In an arm 38 of shaft 9a is journaled an element 38 having internal teeth in mesh with pinion 37 and having attached thereto an insulating disk 39 equipped with a metal circuit-closing strip 40. An insulating shell 41 carried by element 38 has a central contact 42, permanently engaged by strip 40, and contacts 43 arranged at equal intervals and in a circle around contact 42. (Parts 38 to 43 constitute a 70 well-known type of distributor.) An insulated high-tension conductor 44 is connected to contact 42. Insulated distributing conductors 45 lead from the respective contacts 43 through suitable passages provided in housing 34, collar 9b 75

and head 9 of the rotor and through bores 47 in the rotor partitions 43 to the respective spark-plugs, of course grounded.

Housing 3 is closed at its outer end by a wall 48 to form a lubricant reservoir. In said wall axially of the engine is fixed one terminal of a crank 49 whose other terminal finds a bearing in an arm 50a of an annular housing 50 fixed to crank 27, being therefore with the crank an extension of the piston. This housing has radial cylinders 51 communicating therewith and each provided with an inlet port 51a. In each cylinder is a tubular piston 52 whose bore provides a valve-seat 52a closed on the suction stroke of the piston by a ball-valve 53. Each piston is connected with the crank 49 by a link 54. In the rotation of the cylinders around the main axis of the engine or with the crank 27 oil is drawn from the reservoir and impelled through the bore 55 of shaft 17 and then into spaces 56 formed in the piston blades, from which it issues via ports 57 of the blades to between their outer margins and the rotor shell. (To form the spaces 56 and ports 57 each blade may be in two halves, as shown by Fig. 1, each half being machined out at its inner face.) Issuing from the right hand end of bore 55 past a spring-closed valve 58 it finds its way via ports 59 to the space 60 to the left of wall 36 of housing 34, thus lubricating the gearing in said space, from whence it returns to the reservoir via a pipe 61. The oil is also pumped from the reservoir through the bore 49a of crank 49 and via a pipe 62 to a space 63 between the cylinder and rotor, 64 being a return pipe connecting said space with the pipe 61. Pipe 62 terminates at a suitable pump 65 here of the rotary type and driven by gearing 66 from a gear 50b which closes the end of housing 50, the pump of course discharging to the reservoir.

Where provision for sealing between two adjoining surfaces (for instance at 22) is required the novel sealing device of Figs. 12 to 14 may be used. A number (no less than three) of elastic flexible strips 67 are arranged in laminated order but with spaces between them. The spaces are occupied by separators, 68, but each separator is unopposed by one in the next adjoining space and when this arrangement is preserved throughout the length of the device, it is subject to yield through the planes of the strip at any point in such length. The parts will usually be of metal, welded together. Figs. 12 and 14 show two such groups of parts, those of one group having the strips presented edgewise to the planes of those of the other group.

The high tension conductor extends to a coil 69 fast to housing 34 and having a metal annulus connected therewith and comprising rings 70 and 71 joined by metal pins 72, the annulus being insulated at 73 from and fixed in concentric relation to the outer wall of housing 34. On the outer ring wipes a contact 74 to which one lead from the energy source may be connected, the other lead being connected to a contact 75 to wipe against said wall of the housing 34, both contacts being arranged in housing 2.

Having thus fully described my invention, what I claim is:

1. In combination, a cylinder having openings in pairs offset from each other axially of the cylinder and having the openings of each pair forming an intake and exhaust and the two intakes having leads in one rotative direction on the exhausts, a hollow cylindrical rotor coaxial with and in the cylinder, a piston in and coaxial with

the rotor, said rotor and piston respectively having pairs of partitions extending lengthwise of the cylinder axis and alternating with each other and together forming in the rotor four independent working spaces and the rotor having ports leading to the respective spaces and the alternate and remaining ones of such ports entering the rotor at points in the zones of and adapted to communicate with the respective pairs of openings, and means intergearing the rotor and piston for rotation in a common direction and with retardation of the piston at two substantially equal intervals in each cycle of rotation of the rotor, one pair of openings and the pair of ports communicating therewith having leads on the other pair of openings and ports, respectively, in the same rotative direction and to substantially equal extents.

2. A rotary internal-combustion engine including a cylinder having openings in pairs offset from each other axially of the cylinder and having the openings of each pair forming an intake and exhaust and the two intakes having leads in one rotative direction on the exhausts, a hollow cylindrical rotor coaxial with and in the cylinder, a piston in and coaxial with the rotor, said rotor and piston respectively having pairs of partitions extending lengthwise of the cylinder axis and alternating with each other and together forming in the rotor four independent working spaces and the rotor having ports leading to the respective spaces and the alternate and the remaining ones of such ports entering the rotor at points in the zones of and adapted to communicate with the respective pairs of openings, means to fire the charges in said spaces, and means intergearing the rotor and piston for rotation in a common direction and with retardation of the piston at two substantially equal intervals in each cycle of rotation of the rotor, one pair of openings and the pair of ports communicating therewith having leads on the other pair of openings and ports, respectively, in the same rotative direction and to substantially equal extents.

3. A rotary internal-combustion engine including fixed structure having a cylinder, a hollow cylindrical rotor coaxial with and in the cylinder, a piston in and coaxial with the rotor, there being at least one partition on one and two partitions on the other of the parts formed by the rotor and piston and said partitions being within and extending lengthwise of the rotor interior and together forming in the rotor two working spaces and the first-named partition being between the other two, electric ignition devices arranged in the rotor and respectively exposed to said spaces, means intergearing the rotor and piston for rotation in a common direction and with retardation of the piston at two substantially equal intervals in each cycle of rotation of the rotor, the engine having means to admit successively to said spaces the fuel and successively discharge therefrom the combustion products, a rotary distributor carried eccentrically by the rotor exterior of the cylindrical, a gear on said structure concentric with the cylinder and in mesh with the distributor and conductors for the respective ignition devices extending thereto from the distributor.

4. A hollow cylindrical rotor for an engine of the class described having an inward partition extending lengthwise of its interior and having a hole to receive an ignition device and extending from the perimeter of the rotor through the par-

- tion to one side thereof within the interior of the rotor and in bias relation to a diameter of the rotor cutting the partition.
5. The rotor set forth in claim 4 characterized by having another hole to receive a second ignition device and extending from the perimeter of the rotor through the partition to the other side thereof within the rotor interior and in bias relation to said diameter and the first hole.
10. 6. The combination of the cylinder-including structure of a rotary engine and an explosion-rotated element in and coaxial with and fitting the cylinder and projecting therefrom, said structure having endwise of the cylinder a lubricant reservoir receiving the projecting part of said element and an eccentric bearing portion therein, a cylinder extending laterally from said part of said element and within the reservoir and having an inlet, a tubular piston in the latter cylinder and operatively connected with said bearing portion, said element having a passage leading therethrough to its surface adjacent to the first cylinder and forming with the interior of the second cylinder a lubricant passage, and 25 a valve arranged to close the lubricant passage on the suction strokes of the piston.
7. In combination, with the hollow rotor of an engine of the class described having opposed axial openings, a piston including a shaft journaled in said openings and having a longitudinal groove, and a piston blade seated in the groove and having lugs projecting into said openings.
- 30 8. In combination, with the hollow cylindrical rotor of an engine of the class described, a piston including a shaft coaxial with the rotor and having opposed longitudinal grooves and a lon-
- gitudinal slot joining the grooves, and blades arranged in the respective grooves and extending to the inner cylindrical surface of the rotor, one of the blades having passage means extending therethrough from the slot toward said surface and the shaft having means to admit lubricant to the slot.
9. In combination, a cylinder having openings in pairs offset from each other axially of the cylinder and having the openings of each pair forming an intake and an exhaust and the two intakes having leads in one rotative direction on the exhausts, a hollow cylindrical element coaxial with and in the cylinder, another element coaxial with and in the first-named element, 15 said elements respectively having pairs of partitions extending lengthwise of the axis of the cylinder and alternating with each other and together forming in the first-named element four independent working spaces and said first-named element having ports leading to the respective spaces and the alternate and remaining ones of such ports entering said first-named element at points in the zones of and adapted to communicate with the respective pairs of openings, and means intergearing the two elements for rotation in a common direction and with retardation of one element at two substantially equal intervals in each cycle of rotation thereof, one pair of openings and the pair of ports communicating therewith having leads on the other pair of openings and ports, respectively, in the same rotative direction and to substantially the same extent.
- EDWARD WHRITENOUR. 35
